TONE ARM CONTROL FOR RECORDS OF
DIFFERENT DIAMETERS

Enzo Ascoli, Sainte-Croix, Switzerland, assignor
to Paillard S. A. (Paillard A. G., Paillard
Limited)

Application June 17, 1946, Serial No. 677,246
In Switzerland March 21, 1946

7 Claims. (Cl. 274—15)

1

In talking machines provided with a mechanism for changing discs automatically, the arm of the pick-up is actuated, after the audition of a disc, by actuating members producing its vertical and horizontal movements according to a determined cycle. The various phases of this cycle are:

1. Lifting of the arm of the pick-up.
2. Pivoting of the arm of the pick-up about a vertical axis in order to withdraw it from the path traversed by a disc falling on to the turntable.
3. Pivoting of the arm about a vertical axis in the opposite direction for bringing the needle of the pick-up above the start of the disc to be played.
4. Lowering of the arm of the pick-up.

It will be evident that the amplitude of the stroke of entry of the arm (movement mentioned under Number 3) is a function of the diameter of the disc to be played and must be defined very exactly in order to avoid deterioration of the disc or of the pick-up.

In fact if this stroke is too large the needle of the pick-up comes, during the lowering of the arm, into contact with the part of the disc carrying the record and the start of this is lost for the listener. On the contrary when this stroke is too short, the needle of the pick-up may escape the outer edge of the disc which is liable to cause a deterioration of the pick-up.

In known devices for controlling the cycle of movements of the arm of the pick-up, the actuating member producing the entry of the arm is generally formed by a cam on which slides a pusher connected mechanically to the pick-up arm. It will be evident that the angular stopping position of the pick-up, which is a function of the lift of the pusher produced by the cam, is subjected to unsettled actions due to clearances and inaccuracies in mounting of the various members which connect the said pusher mechanically to the pick-up arm. But the inaccuracy which may be tolerated for the angular position of the arm is extremely restricted as the diameter of the recorded portion is variable from one disc to another and the external diameter of the disc also varies from one disc to another. It thus follows that known devices require—

1. Very great precision in the parts connecting the control cam to the pick-up arm.
2. Effecting adjustments in the mounting for

2

adjusting the angular stopping position of the arm.

Finally, after a predetermined duration of operation, as the clearances increase the precision of the position of the arm is no longer ensured.

My invention has for its subject a device for controlling the movements of the pick-up arm of a talking machine having a disc turntable and provided with a mechanism for changing the discs automatically.

This device is distinguished from known devices by the fact that it is provided with a member pivoting about a vertical shaft connected mechanically to the pick-up arm, this member co-operating with two actuating members pivoted co-axially to the latter and of which the first, connected mechanically to a member for controlling the horizontal movements of the arm carrying the pick-up, acts against the action of the second of these members which is subjected to the action of a spring tending to move the pick-up arm in the direction of the centre of the disc turntable, a stop, adjustable in position, being provided for defining the angular stop position of the said second actuating member and thus producing the stopping of the movement of the pick-up arm in an angular position corresponding with the beginning of a disc to be played resting on the disc turntable.

Another object of my invention concerns, in combination with a pick-up arm of a talking machine having a disc turntable and mechanism for changing discs automatically, a device for controlling the movements of said pick-up arm comprising a member pivoting about a vertical axis and connected mechanically to said pick-up arm, two actuating members pivoted co-axially with said first member, said actuating members co-operating with said first member, a second member adapted to control the movements of said pick-up arm, said second member being connected mechanically to one of said actuating members, means for applying a torque to the other of said actuating members tending to move said pick-up arm in the direction of the centre of the said disc turntable, the first of said actuating members being moved against the action of the second of said actuating members, and an adjustable stop, said stop being adapted to define the angular stopping position of said second actuating mem-

ber and thus producing the stopping of the movement of said pick-up arm in an angular position corresponding with the beginning of a disc to be played and resting on said turntable.

An object of my invention is to prevent relative movement between the pick-up arm and supporting members. Still another object of my invention is in combination with a pick-up arm of a talking machine having a disc turntable and mechanism for changing discs automatically, a device for controlling the movements of said pick-up arm of the kind described and including a cam on the first of said actuating members, and transmission members between said cam and said pick-up arm, said cam and transmission members serving to produce the vertical movements of said pick-up arm, a sleeve moving about a vertical axis, said actuating members being pivotally mounted on said sleeve, said transmission members including a pivotally mounted bell crank lever, a pusher passing freely through said sleeve and a supporting member at the upper end of said pusher, one arm of said bell crank lever co-operating with said cam and the other arm of said bearing member on said pick-up arm, said bearing member co-operating with said supporting member, said bearing member and said supporting member being so arranged relatively to the vertical pivotal axis of said pick-up arm and their nature and size are so selected as to create a friction resistance torque which is sufficient to oppose relative movement between said bearing and supporting members under the action of a torque created by the inertia of the said pick-up arm when its horizontal movement ceases and by reason of the weight of the said pick-up arm when the pivotal axis of the latter is out of the vertical.

One form of construction of the device forming the subject of my invention is shown in perspective view diagrammatically and by way of example in the accompanying drawing, wherein:

Fig. 1 is a perspective view of the device, the members of the latter being in the normal position, that is to say in the position which they occupy during the audition of a disc.

Fig. 2 is a perspective view of the device, the members of the latter being shown in the position which they occupy at the moment of reversing the horizontal oscillatory movement of the pick-up arm.

In the form of construction shown, the arm 1 of the pickup is hinged to a horizontal shaft 2. The latter is carried by a support 3 secured to a sleeve 4 turning in a bearing (not shown) provided in the framework of the talking machine. The sleeve 4 turns about a vertical axis and carries a crank 6 of which the pin 7 is subjected to the action of two actuating members 8 and 9 pivoted freely on the sleeve 4. The first 8 of these members is connected mechanically by a link 10 to a member for controlling the movements of the pick-up arm. The control member is formed by a disc 11 carrying a pin 12 and driven by a shaft 16. The latter is set in rotation at the end of the audition of a disc for the duration of the cycle of operations necessary for changing a disc by known means not shown. The complete cycle of operations is controlled during a single complete revolution of the shaft 16.

The second actuating member 9 is subjected to the action of a spring 13 which tends to produce a movement of the pick-up arm in the direction of the centre of the disc turntable (not shown). The second actuating member 9 carries a pin 14 adapted to co-operate with a stop 15, adjustable

in position, so as to define the angular stopping position of the arm for which the needle of the pick-up is located above the beginning of the disc to be played located on the disc turntable.

5 The stop 15 is formed by a plate having three notches 17, 18, 19 and secured rigidly to a shaft 5 pivoted in the framework of the talking machine. To this shaft is also secured an actuating member (not shown) enabling one of the three notches to be brought into the path of the pin 14. The notch 17 defines the position of the actuating member 9 for which the pick-up arm is located above a standard rest support (not shown). The notch 18 defines a position of the member 9 for which the needle of the pick-up is located above the beginning of a disc of large diameter placed on the disc turntable. Finally the notch 19 defines a position of the member 9 for which the needle of the pick-up is located above the beginning of a disc of small diameter placed on the disc turntable. The operating member, secured to the shaft 5 may be actuated either manually or automatically by a known feeler device which detects the diameter of a disc to be played.

10 20 25 30 35 40 45 50 55 60 65 70 75

The vertical movements of the pick-up arm are controlled by a cam 21 on the actuating member 8. A roller 22, pivoted to the end of one of the arms of a lever 23 oscillating on a shaft, co-operates with the profile of the cam 21. The second arm of the lever 23 acts on a pusher 25 sliding in the interior of the sleeve 4 and passing completely therethrough. To the upper end of the pusher emerging from the sleeve 4, is secured an arm 26 having a bent nose 27 and on which rests the arm 1 carrying the pick-up by means of a bearing surface 20. A lug 28, secured to the pusher 25 and provided with an opening 29 with which engages a pin 30 secured to the framework of the talking machine, prevents angular movement of the arm 26.

The operation of the device described above with reference to the accompanying diagrammatic drawing will be understood readily by examination of the latter.

45 In fact, at the end of the audition of a disc, the last track, which is of increased pitch, produces, by the movement of the great amplitude which it imparts to the pick-up arm and by means of a known control device, the setting in rotation of the shaft 16 for the duration of the complete cycle of operations necessary for the automatic changing of a disc.

50 Of this cycle of operation only the movements imparted to the pickup will be described hereinafter.

The shaft 16 being in rotation in the direction of the arrow A, the pin 12 which occupies the position shown in Fig. 1 (stop position during the audition of a disc) moves up to the diametrically opposite position, shown in Fig. 2. During this movement the link 10 actuates the member 8 and the cam 21 in a counter-clockwise direction from the position shown in Fig. 1. The ramp of the cam 21 produces the lifting of the pickup arm by means of the oscillating lever 23 and the pusher 25. During the operation the angular position of the arm 1 relatively to its pivotal axis remains stationary, the arm 1 pivoting only on its hinge 2. After a predetermined angular movement of the member 8 this comes into contact with the pin 7 and repels the latter, thus producing a pivoting of the arm carrying the pick-up on its vertical axis in a counter-clockwise direction and moving the pick-up away from the axis of rotation of the disc turntable. During this angular

lar movement, the pin 7 comes into contact with the actuating member 9 and repels it against the action of its spring 13. The amplitude of the angular movement of the actuating member 8 is determined by the radius of the circle on which the pin 12 moves. When the latter is in the position shown in Fig. 2, the pick-up is disengaged completely from the disc placed on the disc turntable, that is to say that it is out of the path traversed by a disc falling on to the disc turntable. As the shaft 16 continues its rotation, the link 10 is moved in the reverse direction and actuates the member 8 and the cam 21 in a clockwise direction. As the whole part *a* of the cam 21 is circular, the pick-up arm remains in its raised position during the whole of the first part of its angular movement. On the contrary as the member 8 is retracted, the spring 13 expands and moves angularly the member 9 which actuates the pin 7 and holds it in engagement with the member 8. When the pin 14 comes into engagement with one of the notches of the stop 15, the actuation of the sleeve 4, by the member 9, ceases and the member 8, alone continuing its movement, leaves and completely releases the pin 7 from its mechanical connection connecting it to the member for controlling the horizontal movements of the arm 1. When finally the roller 22 reaches the non-circular part *b* of the cam 21, the lever 23 oscillates on its axis 24. The pick-up arm is lowered under the action of gravity whilst repelling the pusher 25. When the needle (not shown) of the pick-up comes into contact with the surface of the disc to be played placed on the disc turntable, the pusher 25 continuing its movement under the influence of gravity, the nose 27 moves away from the pick-up arm so that the mechanical connection, connecting this to its member for controlling its vertical movements, is interrupted. From this moment the pick-up arm is thus entirely free and the pick-up can follow the movements imparted thereto by the track traced on the disc.

From the foregoing it will be seen that the amplitude of the incoming stroke of the pick-up arm and its angular stop position above the beginning of the disc to be played, is exactly defined by the stop 15. This position is maintained during the lowering of the arm by reason of the resistance torque produced by the friction between the bearing surface 20 secured to the arm 1 and that of the nose 27. It is possible to select the nature of its surfaces, their dimensions and their arrangements relatively to the vertical pivotal axis of the arm 1, in such a manner that the resisting torque is sufficient for opposing the forces of inertia and balancing the arm when the pivotal axis of the latter is out of the vertical.

It will be understood that the members and elements of the device here described by way of example and with reference to the accompanying drawing may be replaced directly by their equivalents. For example it is possible, for reducing the torque necessary for producing the horizontal movements of the arm 1, to cause the pusher 25 to pivot in synchronism with the arm 1 by securing the pin 30, for example, to the actuating member 9. As the latter is in contact with the stop 15 during the lowering of the arm 1 it defines the angular position of the nose 27 during this movement of the arm so that the angular position of the latter is held by the resisting torque which is opposed by the friction of the bearing surface 20 of the arm 1 resting on the

nose 27 against all relative movements between the latter and the arm 1.

In spite of its great simplicity the device described allows of obtaining a precise control of the movements of the pick-up arm and further has the advantage of defining in a very precise manner the angular position which the pick-up arm should occupy so that the needle of this comes into contact with the beginning of the disc to be played placed on the disc turntable.

The necessary torque for causing the pick-up to enter is no longer furnished by the expansion of the spring 13 but by the said friction clutch. In this modified form of construction the operation 15 of the device is similar to that described with reference to the accompanying diagrammatic drawing, the pick-up arm being also subjected to a torque tending to move it towards the centre of the disc turntable.

I claim:

1. In a talking machine having a disc turntable and a mechanism for changing the disc automatically, the combination with a pickup arm, of a device comprising, means supporting the pickup arm in a horizontal position and providing a horizontal pivot for the pickup arm to permit same to swing upwardly and mounted for rotation about a vertical axis, a crank rigid with the supporting means, a pair of actuating members rotatably mounted for engagement with the crank, one of the actuating members carrying a cam, a link connected at one end to the cam carrying actuating member, a control member rotatably mounted and pivotally connected to the other end 25 of the link, yieldable means engaging the other of the actuating members and urging the free end of the pickup arm toward the center of the turntable, an adjustable stop rotatably mounted and engageable in three different positions with the other actuating member and thereby defining a corresponding number of limiting positions of the other actuating member, a member movable vertically and in lowered position having its upper end disengaged from the pickup arm but in raised position frictionally engaging same to prevent relative rotation thereof, fixed means slidably engaged by the vertically movable means to prevent rotation thereof, and means coacting with the cam of the first actuating means and operable thereby and engaging and lifting the vertically movable member to swing the pickup arm about its horizontal pivot.

2. The combination according to claim 1 and wherein the supporting means includes a sleeve receiving the vertically movable member.

3. The combination according to claim 1 and wherein the crank includes a pin engageable by the actuating members.

4. The combination according to claim 1 and 60 wherein the control member includes a disc providing a pivot for the link.

5. The combination according to claim 1 and wherein the other actuating member is provided with a pin and the stop has three notches for the pin.

6. The combination according to claim 1 and wherein the vertically movable member is guided by the supporting means and carries at its upper end an arm having a bent nose engaging a bearing surface on the pickup arm.

7. The combination according to claim 1 and wherein the lifting means is a bell crank.
